POCKET DUPLICATOR

William F. O'Gorman, New York, N. Y.

Application August 24, 1943, Serial No. 499,807

2 Claims. (Cl. 101—125)

1

My invention relates to a pocket duplicator and its object is to provide a small compact device to be used like a rubber stamp for making impressions from a stencil. Another object is to provide a complete outfit enclosed in a small case for making stencils and using them.

These and other objects of the invention will appear in the following specification in which I will describe a duplicator outfit which is made according to and embodies the present invention, the novel features of which will be set forth in the appended claims.

Referring to the drawing:

Figure 1 is a perspective view of what I now consider a preferred form of my duplicator. In this view the parts are unfolded and no stencil sheet is shown.

Fig. 2 is a perspective view of a stencil holder with a platen and a stencil sheet therein.

Fig. 3 is a transverse section of the parts shown in Fig. 2.

Fig. 4 is a perspective view of the stencil holder and a stencil sheet therein without a platen.

Fig. 5 is a transverse section of the parts shown in Fig. 4.

Fig. 6 is a transverse section of the parts shown in Fig. 1 with a stencil and with the parts folded together and ready for use.

Fig. 7 is a perspective view of the parts shown in Fig. 6 and of a protective cover therefor.

Fig. 8 is a perspective view of a plurality of stencil sheets surrounded by a wrapper.

Figs. 9 and 10 are perspective views respectively of a stylus and ink spreader which form parts of the outfit.

Fig. 11 is an actual full size perspective view of a case with all parts of the outfit therein.

20 designates a rectangular block of wood or other suitable material on one side of which, designated by 21, an ink pad 22 is attached. The ink pad is narrower and shorter than the side 21 of the block and is centrally located therein.

20 is a cover sheet of thin fibre board of a width equal to the length of the block. This is creased transversely to form parallel fold lines which subdivide the cover sheet into different sections. The first of these sections forms a tab 31 which is arranged to extend away from the side 23 of the block, as shown in Fig. 6, or folded down to a position parallel with the side 23 of the block when the device is not in use, as shown in Fig. 1. The next section of the cover sheet, designated by 32, extends from the fold line between it and the tab 31, which is spaced from the edges 24 of the block as shown at 33, to the op-

2

posite edge 25 and is affixed to the block by suitable means, such as staples 34.

Next is a narrow section 35, the width of which is approximately the same as the thickness of the block and is adapted to cover its edge 25. The section designated by 36 corresponds to the size and shape of the side 21 of the block to which the ink pad is affixed. A portion of this section, which corresponds to the size and shape of the ink pad is cut away as shown at 36A.

37 and 38 are narrow sections, the first of which is adapted to overlie the edge 24 of the block and the second is of a width which corresponds to the distance of the fold line between the tab 31 and the edge 24 of the block. The section 39 is a tab which corresponds in size and shape to the tab 31.

40 is a stencil sheet holder which comprises a sheet of stiff paper or the like, transversely folded on a median line 41 to form overlapping layers 42, 43, the width of which corresponds to the length of the block 20. An opening 44 of the size and shape of the ink pad 22 is cut out of the upper layer 42. At the ends of this opening parallel lines 45, 45 are printed which are spaced 25 apart the distance between the lines printed by a standard typewriter.

A stencil sheet 46 of a length equal to the length of the block 20 and a width approximately equal to the width of the block and two of its edges 24, 25 is placed between the layers 42, 43 with one of its edges abutting the fold line 41 between them. 47 is a platen with a slightly roughened surface placed under the stencil sheet.

A convenient way of making a stencil is to inscribe within the opening 44, the desired matter to be duplicated by a stylus such as that shown at 50 in Fig. 9.

Another way of making a stencil is to put a stencil sheet 46 in a stencil sheet holder 40 without the platen, as shown in Figs. 4 and 5, place the stencil sheet holder on the platen of a typewriter and print the desired matter with the typewriter, guided by the lines 45.

After the stencil sheet 46 has been prepared, 45 it is removed from the stencil holder and placed on the block 20 over the previously inked pad 22 with its paper side against the pad and overlying the top 21 of the block and its opposite edges 24 and 25. The sheet 46 is then folded around 50 the block 20 and its section 36 will hold the stencil sheet 46 in position. The tabs 31 and 39 when in raised overlapping position, as shown in Fig. 6, may be grasped between the fingers and the insignia inscribed on the stencil sheet 46 stamped 55 on a piece of paper or other desired surface.

When not in use the tabs 31 and 39 are folded down into parallelism with the surface 21 of the block and the device slipped into a protective cover 60 (Fig. 7). The side 61 of this cover is raised as shown, to form a space between the inner side thereof and the ink pad 22 and the overlying stencil sheet. The side 61 of the cover and its opposite side 62 are tapered at one end so that the outer corners of the inserted duplicator are exposed to facilitate its insertion and removal. The rear end of the protective cover (not shown) is closed.

Although in the small size shown the opening 44 is only three quarters of an inch wide, this is sufficient to receive three lines of type-writing.

A bundle of stencil sheets is shown in Figs. 8 and 11 surrounded by a wrapper 49. In Fig. 11, 80 designates a case with folding flaps 81, 82 and 83 at one end with the various parts of the outfit which have been described therein, together with a bottle of ink 90 and ink dauber 91. A perspective view of the dauber appears in Fig. 10.

One of the features of this invention is that it provides an arrangement which enables the use of a very small stencil which is easily manipulated and is extremely compact so that the duplicator and all of the parts of the outfit may be enclosed in a pocket sized case. I realize that modifications may be made within the spirit and scope of the invention and intend no limitations other than those imposed by the appended claims.

What I claim is:

1. A duplicator comprising a flat rigid block, an ink pad affixed to and projecting from one side of the block and being of smaller transverse dimensions than those of said side of the block, a stencil sheet arranged to lie over the pad and

5
10
15

opposite edges of the block, and a cover sheet arranged to be folded around the block and over the parts of the stencil sheet on the edges of the block, the section of the cover sheet over the side of the block having the pad thereon corresponding in size and shape to those of said sides of the block and being constructed with an opening therein of smaller dimensions than those of said side of the block, the ends of said cover sheet forming overlapping finger tabs.

2. A duplicator comprising a flat rigid block, an ink pad affixed to and projecting from one side of the block and being of smaller transverse dimensions than those of said side of the block, a stencil sheet arranged to lie over the pad and opposite edges of the block, and a cover sheet arranged to be folded around the block and over the parts of the stencil sheet on the edges of the block, the section of the cover sheet over the side of the block having the pad thereon corresponding in size and shape to those of said sides of the block and being constructed with an opening therein of smaller dimensions than those of said side of the block, the ends of said cover sheet forming overlapping finger tabs projecting from the block and arranged to be folded down onto the block.

WILLIAM F. O'GORMAN.
